UNITED STATES PATENT OFFICE.

JOSEPH PLATTENBURG, OF MCKEESPORT, PENNSYLVANIA.

CAR-FLOOR FRAME.

SPECIFICATION forming part of Letters Patent No. 379,978, dated March 27, 1888.

Application filed December 5, 1887. Serial No. 256,977. (No model.)

To all whom it may concern:

Be it known that I, JOSEPH PLATTENBURG, of McKeesport, Allegheny county, Pennsylvania, have invented certain new and useful 5 Improvements in Car-Floor Frames, of which the following is a specification.

The invention pertains to floor-frames for railway-cars, and relates to improvements in the trussing system, by means of which with 10 comparatively light timbers extraordinary vertical stiffness is secured.

My improvements will be readily understood from the following description, taken in connection with the accompanying drawings, 15 in which—

Figure 1 is a perspective view of the car-floor frame exemplifying my improvements, and Fig. 2 an enlarged perspective view of one of the strain-blocks.

20 In the drawings, A indicates the two sills; B, the intermediate floor-timbers; C, the two end sills; D, the two body-bolsters; E, the two cross-frame tie-timbers, which, with the previously-mentioned timbers, are to be framed 25 up, as usual; F, strain-blocks disposed centrally over the body-bolsters and reaching across from sill to contiguous intermediate floor-timbers; G, holes transversely through the strain-blocks, a pair of holes being located 30 near each end of each block and near the top thereof; H, flanges formed upon the ends of the strain-blocks, and serving as means by which the strain-blocks may be rigidly secured by bolts holding the flanges in vertical trans- 35 verse gains in the sills and intermediate floor-timbers; J, end rods inclined downwardly from the strain-blocks to and through the end sills, there being a pair of rods for each strain-block, one of the rods lying near the appropriate 40 sill and one near the appropriate intermediate floor-timber, each rod being provided with a nut at each end seating against appropriately-beveled nut-seats on the end sill and strain-block, respectively; and K, body truss- 45 rods provided with nuts at each end, each rod extending from a strain-block toward and under the cross-frame tie-timbers, thence upwardly and into engagement with the appropriate strain-block at the other end of the car, 50 two of these body truss-rods engaging each strain-block, one rod lying as closely as practicable against the inner side of the appropriate sill, while the other rod lies similarly near the outer side of the appropriate intermediate 55 floor-timbers.

The flooring over the floor-frame should be removable or be provided with traps over the body-bolsters, so that the rod-nuts at the strain-blocks can be gotten at from above. The end rods can be strained by means of the nuts 60 at either end sill or strain-blocks. By removing the inner nuts on these end rods the rods may be readily withdrawn outwardly through the end sills, thus rendering construction, repairs, and renewals of these rods a matter of 65 ease.

The body truss-rods strain from positive points over the body-bolsters, which represent the supporting-points in the length of the car. These rods are put under proper strain by 70 means of their end nuts. These nuts, being removed, permit of the rods being readily removed for repair or renewal by first shifting the rod endwise until it becomes disengaged from one strain-block, then lowering the disengaged end, and then shifting the rod endwise until the other end becomes disengaged—work 75 easily performed by one man.

In ordinary car-floor-frame construction the truss system fails to hold up the middle of the 80 car satisfactorily, even with very heavy timbers. My improved construction yields satisfactory resistance to deflection with comparatively light timbers, and with equivalent timbers permits the car-loads to be largely in- 85 creased.

The term "timbers" may be taken as meaning either the wooden timbers usually employed or their metal substitutes sometimes employed. 90

I claim as my invention—

1. In a car-floor framing, the combination, substantially as set forth, with the sills, intermediate floor-timbers, end sills, body-bolsters, and cross-frame tie-timbers, of strain-blocks 95 disposed over the body-bolsters and secured to the sills and intermediate floor-timbers, end rods engaging the strain-blocks and end sills, and body truss-rods engaging under the cross-frame tie-timbers and provided with end nuts 100 engaging the strain-blocks.

2. In a car-floor frame, the combination, substantially as set forth, with the sills, intermediate floor-timbers, end sills, body-bolsters, cross-frame tie-timbers, end rods J, and body 105 truss-rods K, of strain-blocks F, provided with holes G and with flanges H.

Witnesses: JOSEPH PLATTENBURG.
